FIG. 2

UNITED STATES PATENT OFFICE.

JACOB B. STRUBLE, OF SAN FRANCISCO, CALIFORNIA, ASSIGNOR TO THE UNION SWITCH AND SIGNAL COMPANY, OF SWISSVALE, PENNSYLVANIA, A CORPORATION OF PENNSYLVANIA.

RAILWAY SIGNALING.

1,092,460.

Specification of Letters Patent.

Patented Apr. 7, 1914.

Original application filed March 4, 1904, Serial No. 196,474. Divided and this application filed July 25, 1913. Serial No. 781,084.

To all whom it may concern:

Be it known that I, JACOB B. STRUBLE, a citizen of the United States, residing at San Francisco, county of San Francisco, and 5 State of California, formerly residing in the borough of Manhattan, city, county, and State of New York, have invented certain new and useful Improvements in Railway Signaling, of which the following is a specification.

10 The present application is a division of my copending application filed March 4, 1904, Serial No. 196,474, for railway signaling.

15 My invention relates to railway signaling, and especially to a signaling system for electric railways wherein one or both of the track rails are used as a return conductor for the propulsion current.

20 It is customary in electric railways to employ direct current for operating the car on train motors and to employ one or both of the rails as a return conductor for the propulsion current.

25 In the present invention I employ alternating current in the track circuits of the signaling system, to which translating mechanisms included in the track circuits, are responsive in their control of the railway 30 signals.

I will describe a railway signaling system embodying my invention and then point out the novel features thereof in claims.

In the accompanying drawings, Figure 1 35 is a diagrammatic view illustrating a portion of an electric railway having a signaling system embodying my invention applied thereto. Fig. 2 is a detail view of an impedance in the form of a reactance or 40 choke coil, which may be employed in my invention.

Similar letters of reference designate corresponding parts in the two views.

Referring now to the drawings and particularly to Fig. 1, in the practice of my invention one of the lines of rails of the railway is divided into a series of sections 1, 2, 3, etc., by means of insulation at suitable points, while the other line of rails 4 45 is preferably made electrically continuous. The sections 1, 2, 3, etc., may be of any desired length and in the art each section and the opposite portion of the continuous rail 4 is generally termed a "block section."

6^a designates a direct current generator and 6^b a feed conductor extending therefrom and along the line of railway and from which current is obtained for the motors of the cars traveling along the railway. The return for the direct or propulsion current is 60 through one or both track rails, they being bonded or joined together for this purpose in the manner hereinafter described.

14 designates a railway signal, at least one being provided at the beginning of each 65 block section. The railway signals 14 may be of any desired construction and they each preferably comprise a semaphore and mechanism or means for moving the semaphores from one position of indication to 70 another.

5 designates an alternating current generator. One pole of the alternating current generator is here shown as being connected with the line of rails 4, while the other pole 75 of the generator 5 is connected with a conductor 5^a extending along the line of railway, and which, at some suitable point, for example, at the end of the railway, is electrically joined to the line of rails 4. 80

6 designates transformers, at least one transformer being provided for each block section.

As shown in the drawings, the primary windings of the transformers are in series 85 with the conductor 5^a, and their secondary windings are electrically connected to the opposite lines of rails comprised in each block section. It will be understood that other arrangements of the conductors extending from the alternating current generator 5 may be provided as well as other arrangements of the primary windings of the transformer. The employment of transformers permits of a high tension current in the transmission conductor 5^a and the use of low tension currents in the track 90 circuits. 95

To prevent an excessive amount of alternating current flowing in a track circuit 100 when a train is in the block section, a resistance 7 is arranged in the track circuit, (as shown, in one of the connections of the secondary winding with track rail) or each transformer 6 may be built with such resistance as is well known in the art. The track circuit of each block section comprises all or portions of the track rails of 105

the block section, a transformer or the secondary winding thereof, and a translating mechanism or device.

8 designates translating mechanisms or devices, one being provided for each track circuit. Each translating mechanism is in the form of a relay, the coil or coils 18 of which are included in the track circuit. The armature 19 of the relay is pivotally mounted in operative relation to the poles of the magnet core energized by the coil or coils 18. The form of translating device and its operation is more particularly set forth in my Patent No. 819,323, issued May 1, 1906. This form of translating mechanism as set forth in the patent hereinbefore referred to is responsive to the alternating current in the track circuit for one of its operations to control a local circuit 13, which circuit includes a source of electrical energy, and a controlling device of the mechanism of the signal 14, and when the alternating current is shunted from the coil or coils 18, for example, by the wheels and axles of the train on the track rails of the track circuit in which the translating mechanism is included, it will respond to again control the circuit 13. In other words, when alternating current is flowing through the coil or coils 18, the armature 19 will move to close the circuit 13 and when alternating current is shunted from the coil or coils 18, the armature 19 will move to open the circuit 13. In both conditions of the circuit 35 the mechanism of the railway signal will be affected to have the semaphore thereof give different indications. Any other form of translating mechanism may be employed.

17 designates impedances in the form of reactance or choke coils (see Fig. 2), which may be constructed in accordance with the rules well known in the art. The coils may be employed to connect adjacent ends of the insulated track sections, and they may also be connected across the wires or conductors connecting the translating mechanisms with the track rails. These coils will permit of direct current flowing through them but will oppose the flow of alternating current through them, the effect, therefore, being to confine alternating current to the several track circuits and to permit direct current to pass from the track rails of one track circuit to the track rails of another track circuit. In other words, the direct or propulsion current for the car motors may be flowing through both track rails as a return without in any way affecting the apparatus connected therewith. Each coil is made 60 with low ohmic resistance so as to form an easy path for direct current from rail to rail, while the flow of alternating current is opposed by the reactive effect of self-induction so that the reactance coil has a choking effect on the alternating current but not on

the direct current. The coils and the other instruments connected with the track circuits will be constructed in the proper proportions and with the proper resistances to carry out my invention.

Having thus described my invention, what I claim is:

1. In combination with a railway having one rail electrically continuous and the other divided by insulation into track sections, of a direct current generator having one pole connected with the track rails, reactance coils connecting adjacent ends of the insulated sections, reactance coils connecting the sections with the continuous rail, and a signaling system, said system comprising track circuits, an alternating current supply for each track circuit and a translating mechanism for each track circuit which is operated from the alternating current in the track circuit. 75

2. In an electric railway signaling system employing a closed signal controlling track circuit, a plurality of block sections, one rail being divided into insulated sections corresponding to the block sections, a signal for each block section operable by an alternating current, a source of alternating current for said signals, a source of direct current for propelling the railway cars, means for permitting the direct current to pass from one insulated rail section to another and for preventing alternating current from passing from one insulated rail section to another, and an inductive bond connecting the rails comprised in each block section. 80

3. In a system of electrical distribution and signaling for railways, the combination of two sources of electrical energy delivering currents differing in character, outgoing feeder conductors, two track rails, one continuous and the other divided into sections to form blocks, a reactance device interposed between each two adjacent sections, and a reactance device connected across the rails of each block. 95

4. In combination, a railway the track-way of which is divided to form track sections, a direct current generator having one terminal connected with the track rails, reactance coils connecting adjacent ends of the sections, reactance coils connecting the opposite rails of the sections, and a signaling system comprising track circuits for the sections, a source of alternating signaling current for each track circuit, and a translating mechanism for each track circuit which is controlled by the alternating signaling current in the track circuit. 105

5. In combination, an electric railway both track rails of which are included in the circuit for the propulsion current, a source of propulsion current of one character, a plurality of block sections formed by in- 110 120 125 130

sulations in one of the lines of track rails; a source of signaling current connected with the rails of each section and differing in character from the propulsion current, a translating device connected with the track rails of each section, signals controlled by said translating devices, means for permitting the propulsion current to pass from each insulated track section to the adjacent track sections and for preventing the passage of the signaling current, and means for permitting the propulsion current to pass from the insulated rail section of each block section to the other rail and for preventing the passage of the signaling current.

6. In combination, an electric railway both track rails of which are included in the circuit for the propulsion current, a source of direct propulsion current, a plurality of

block sections formed by insulations in one 20 of the lines of track rails, a source of alternating signaling current connected with the rails of each section, a translating device connected with the rails of each section and responsive to the signaling current but not 25 to the propulsion current, signals controlled by said translating devices, reactances connecting the insulated track rail of each block section with the insulated track rail of each adjacent block section, and a reactance for 30 each block section connecting the insulated track rail with the opposite rail.

In testimony whereof I affix my signature in presence of two witnesses.

JACOB B. STRUBLE.
